UNITED STATES PATENT OFFICE.

CHARLES M. SWINGLE, OF CLEVELAND, OHIO.

ELECTROTHERAPEUTIC REJUVENATOR.

1,216,183.

Specification of Letters Patent. Patented Feb. 13, 1917.

Application filed September 18, 1916. Serial No. 120,799.

To all whom it may concern:

Be it known that I, CHARLES M. SWINGLE, a citizen of the United States, residing at Cleveland, in the county of Cuyahoga and State of Ohio, have invented a new and useful Electrotherapeutic Rejuvenator, of which the following is a specification.

The present invention appertains to an apparatus for the treatment of diseases and the like, and aims to provide a novel and improved electro-therapeutic rejuvenator for the organs of regeneration, for treating diseases of those organs, and for diseases and affections of parts adjacent to those organs especially, and also for the treatment of all other diseases where osmotic, cataphoretic and physiological action may be stimulated and corrected under the influence of magnetic force.

It is the object of the invention to provide a device of the nature indicated utilizing electrical current in connection with a suitable medicament for the treatment of diseases, the medicament being applied to the tissues by the assistance of the electrical energy which produces heating, magnetic and therefore osmotic and cataphoretic effect.

It is also the object of the invention to provide an implement of the nature indicated composed of a novel assemblage of the component elements, the parts being readily assembled and separated, and the device being comparatively simple, compact and inexpensive in construction, as well as being convenient, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a longitudinal section of the device, portions being shown in elevation.

Fig. 2 is a cross section on the line 2—2 of Fig. 1.

Fig. 3 is a sectional detail to show the grooves or recesses in the shell.

In carrying out the invention, there is provided a core 1 of soft iron or other magnetic material, upon which is mounted a resist-

ance coil 2 comprising a winding of insulated wire. An annulus 3 of hard rubber or other insulating material is threaded upon the inner end of the core 1 and one end of the coil 2 rests thereagainst, while a disk 5 of hard rubber or other insulating material is secured to the outer end of the core 1 by means of a securing screw 6, and bears against the opposite end of the coil 2, said coil being held upon the core 1 between the annulus 3 and disk 5. The terminals 4 of the coil 2 extend through suitable apertures provided in the annulus 3.

A tubular shell or case 7 of hard rubber or other insulating material is slipped over the coil 2 and disk 5 and has its outer end closed and preferably rounded, while the inner end 8 of the shell 7 is open, and is threaded upon the annulus 3, whereby to hold said shell in place to house or inclose the coil. The shell 7 is provided with grooves or superficial recesses 9 in its periphery which can extend longitudinally, spirally or in any other direction, for receiving a suitable medicament.

A sleeve or reducer 10 of hard rubber or other insulating material has its larger end threaded upon the annulus 3 and abutting against the open end 8 of the shell 7, the sleeve 10 and shell 7 having their adjacent ends flush. The reduced or smaller end 11 of the sleeve 10 is internally threaded, and receives the threaded extension 12 of a connecting plug or member 13 bearing against said end 11. A pair of contact members 14 extend longitudinally through the plug 13 and are socketed for engaging pins of another member for electrically connecting the coil 2 with conductors leading to a suitable battery or other source of electrical energy. The members 14 provide binding posts projecting into the sleeve 10 and to which the terminals 4 of the coil 2 are attached. The terminals 4 are attached to the members or binding posts 14 before the sleeve 10 is attached to the annulus 3 and plug 13, and the threads at the opposite ends of the sleeve 10 are right and left handed, whereby after the terminals 4 are connected to the binding posts 14, the sleeve 10 can be simultaneously threaded into engagement with the annulus 3 and plug 13 to assemble said parts, the terminals 4 being slackened and housed within the sleeve 10. The plug 13 can be attached to any suitable connecting member, for supplying the coil 2 with electrical en-

- ergy, for heating the device to the desired temperature, and for creating a magnetic field to assist in the curative properties of the device. The current can be controlled 5 by a suitable rheostat, and the device can be manipulated in any suitable manner, according to the circumstances. The medicament applied to the grooves 9 will be heated by the electrical energy and by the heat of 10 the tissues, and osmotic action is rendered both rapid and agreeable under the influence of magnetism.

The device can also be used for the treatment of ulcers or sores on ordinary surfaces 15 of the body, and a number of the instruments can be disposed side by side and inclosed in a single casing or covering, or otherwise assembled, whereby the device can be applied over the liver or other part of 20 the body with telling effect.

Having thus described the invention, what is claimed as new is:

1. An electro-therapeutic rejuvenator embodying an electrical heating coil, and a 25 member adjacent to said coil to be heated thereby and having superficial medicament holding recesses.
2. An electro-therapeutic rejuvenator embodying a shell having superficial medicament holding recesses, and an electrical heating coil inclosed therein.
3. An electro-therapeutic rejuvenator embodying a core, an electrical heating coil mounted thereon, members attached to the 35 ends of the core with the coil between them, and a shell slipped over said coil having superficial medicament holding recesses and having an open end attached to one of said members.
4. An electro-therapeutic rejuvenator embodying a core, an electrical heating coil mounted thereon, members attached to the 40 ends of the core with the coil between them, a shell slipped over said coil having superficial medicament holding recesses and hav-

ing an open end attached to one of said members, the other end of said shell being closed, and the terminals of the coil extending through said member.

5. An electro-therapeutic rejuvenator embodying a core, an electrical heating coil mounted thereon, a member upon said core at one end of said coil, the terminals of the coil extending through said member, and a shell slipped over said coil having superficial medicament holding recesses and having an open end attached to said member.

6. An electro-therapeutic rejuvenator embodying a core, an electrical heating coil mounted thereon, a member upon said core 60 at one end of said coil, the terminals of the coil extending through said member, a medicament holding shell slipped over said coil and having an open end attached to said member, a member having a pair of contact 65 members to which the terminals of the coil are connected, and a sleeve disposed between and connecting the first and second mentioned members.

7. An electro-therapeutic rejuvenator embodying a core, an electrical heating coil thereon, a member upon the core at one end of the coil, the terminals of the coil extending through said member, a medicament holding shell slipped upon the coil and having an open end engaged upon said member, a second member having a pair of binding 70 posts to which said terminals are connected, and a sleeve having a larger end engaged upon the first mentioned member and a 75 smaller end engaging the second mentioned member, said sleeve housing the binding posts and terminals of the coil.

In testimony that I claim the foregoing as my own, I have hereto affixed my signature in the presence of two witnesses.

CHARLES M. SWINGLE.
